UNITED STATES PATENT OFFICE.

THOMAS W. KELLEY, OF BROOKLYN, ASSIGNOR TO BUTLER & KELLEY, OF NEW YORK, N. Y.

DESIGN FOR A CARD.

SPECIFICATION forming part of Design No. 19,901, dated June 10, 1890.

Application filed May 6, 1890. Serial No. 350,825. Term of patent 14 years.

To all whom it may concern:

Be it known that I, THOMAS W. KELLEY, of Brooklyn, in the county of Kings and State of New York, have invented and produced a new and original Design for Cards, of which the following is a description, reference being had to the accompanying drawings, which fully illustrate the design.

The prominent feature of the design consists of a rectangular card having the representation of a panel at each end, or on opposite sides thereof, which panels are shown as raised above or lying on the main body of the card, and are of less width than the said body of the card.

AA represent these panels. One of the side edges of each of these panels corresponds with one of the edges or sides B of the body C of the card, and the panels appear to spring from

or to be turned up from the body of the card at these edges and to be folded over upon the card. These panels are of less width than the apparent main body of the card, so that the opposite edges C C of such main body show beyond the panels and serve to offset them or form a depressed ornamenting border along two opposite sides of the folded panels.

What is claimed as new is—

The design for a card herein shown and described, the same consisting of a rectangular card C, having represented as lying upon it two panels A, which panels extend from the sides B of the card toward each other and are of less width than the body of the card.

THOMAS W. KELLEY.
